UNITED STATES PATENT OFFICE

EVERETT M. AIKMAN, OF INDIANAPOLIS, INDIANA

REGULATING DROPPER

Application filed November 3, 1930. Serial No. 492,923.

This invention relates to a combination perforator and valve and dropper for an imperforate perforative seal for a liquid container.

5 It is the practice to merchandise ether for anaesthetic purposes as a liquid in a container which is permanently sealed and provided with a perforative seal. It is the practice to use a safety pin and perforate the seal at 10 two places, one to permit air to enter the container and the other to permit the liquid to drip therefrom, the air opening being to relieve the back pressure or vacuum in the container and permit the free dropping of 15 the liquid.

The opening formed by a safety pin, or the like, is relatively small size. It is objectionable to use any of the operating instruments, because these are sterilized, even 20 though their use as a can opener might not injure them. When holes are initially made in the aforesaid manner, during an operation there is little or no regulation possible and there is little or no directional discharge 25 from the container.

The chief object of the invention, therefore, is to provide a device that may be readily adjusted to a liquid container and so arranged that the anaesthetist may hold the container in one hand and use his fore finger of the said hand for regulating the flow of the liquid from the container and which is also adapted for directional discharge. The device is so arranged also that progressive application of pressure sufficient for perforation will progressively increase the openings for a greater discharge, while a lighter pressure thereon will not enlarge the openings but will serve to partially seal the same, thus 40 acting as an obstruction to the free flow of liquid should the rate of flow be initially greater than that desired.

The chief feature of the invention consists in the unitary construction of a device 45 adapted to accomplish the foregoing object.

The full nature of the invention will be understood from the accompanying drawing and the following description and claims:—

In the drawing, Fig. 1 is a perspective view 50 of a portion of the operator's hand, the liquid

container and the device applied thereto and with the fore finger of the operator in control position.

Fig. 2 is a perspective view of the device removed from the container. 55

Fig. 3 is a central sectional view through the container mouth, seal and the device in operative position.

In the drawing 10 indicates a liquid container suitable for containing ether and the like, which is normally a liquid but which readily vaporizes under atmospheric conditions. The container 10 has the top 11 and the neck 12. The open end in the neck 12 is flared outwardly and extending across the mouth thereof and embracing said flared end of the neck is an imperforate perforative seal 13. This constitutes the standard ether container. To permit the discharge of the ether drop by drop, as required for anaesthetic purposes, there is provided an air hole 14 and a liquid discharge or pouring hole 15. This, as heretofore set forth, is usually performed by jabbing a safety pin at opposite sides of the seal and said safety pin readily passes therethrough. 75

The present invention includes an attachment having a body portion 18 provided with barbs 16 and 17, preferably tapered, saw-tooth, or wedge shaped and in spaced relation. The supporting portion 18 is extended as at 19 and forms a standard or support which terminates in the embracing arms 20, the same including outwardly turned free ends 21. As initially fashioned, the support 19 and the barb body supporting portion 18 extend at an angle of about 150 degrees. 85

The metal constituting the device is preferably readily deformable and bends when pressure is applied to the portion 18 after the arms 20 have embraced the neck 12 of the container for mounting the device upon the container. Continued pressure causes the barbs 16 and 17 to perforate the seal 13 to provide air opening 14 and the pouring opening 15. Continued pressure serves to enlarge said openings to the desired degree and if the said enlargement is excessive or more than that desired, slight pressure upon the body portion 18 will maintain the barbs in 100

the enlarged openings thus formed and serve to reduce the effective area thereof. The liquid which discharges from opening 15 runs out along the tooth 17 and is discharged 5 drop by drop from the dropper extension 22 of the body portion 18. Thus, directional discharge may be obtained through the employment of the aforesaid device.

The device has a further advantage that 10 should the anæsthetist remove his finger from the device, it will not become detached from the container but will remain thereon and thus there is no danger of the device falling into the patient's mouth during the 15 anæsthetizing of the patient should the mask used therein become displaced.

Another advantage inherent in the device is that it may be constructed of relative thin sheet metal and at a single punching and 20 forming operation. In fact, the cost of the attachment is so slight that one can be supplied with every container in much the same fashion that wire cork pullers are supplied with other medicine containers.

25 The invention claimed is:—

1. An attachment mountable on the restricted neck of a container having a perforatable imperforate mouth seal, comprising a pair of substantially encircling neck anchoring arms, an extension therefrom, seal puncturing means carried thereby and a dropper constituting an extension of the first mentioned extension.

2. An attachment mountable on the restricted neck of a container having a perforatable imperforate mouth seal, comprising a pair of substantially encircling neck anchoring arms, an extension therefrom, a pair of seal puncturing wedge shaped members 40 carried thereby, and a dropper constituting an extension of the first mentioned extension.

In witness whereof, I have hereunto affixed my signature.

45 EVERETT M. AIKMAN.
